SEWING MACHINE

Rudolf Naftali and Valentine Naftali, Pelham Manor, and Henry Naftali, Bronx, N. Y., assignors to American Machine and Foundry Company, a corporation of New Jersey

Original application July 19, 1935, Serial No. 32,148, now Patent No. 2,213,965, dated September 10, 1940. Divided and this application June 7, 1940, Serial No. 339,356

17 Claims. (Cl. 112—171)

Our invention relates to sewing machines. More particularly, our invention is concerned with improvements to that type of sewing machine used for making neckties, and disclosed in our Patent No. 1,931,447, dated October 17, 1933, in which there is employed a double pointed needle having its eye located between the points, the opposite ends of which are grasped alternately by the jaws of opposed needle bars arranged in alignment.

This application constitutes a division of our co-pending application, Serial No. 32,148, filed July 19, 1935, for Sewing machines, now Patent No. 2,213,965, granted Sept. 10, 1940.

One object of our invention is to provide a machine of the character described in which the thread is prevented from becoming entangled and thereby broken, during the stitching operation.

Another object of our invention is to provide a machine of the character described, having improved looping mechanism.

An added object of our invention is to provide a machine having means which cooperate with the needle operating mechanism for forming slack in the thread above the work support so that the best possible stitches may be formed.

A further object of our invention is to provide means which engage a portion of the thread after the partial formation of a stitch and pull the thread laterally in order to provide slack and guide the thread for proper disposition with respect to the material being sewed.

Another object of our invention is to provide a machine of the character described, having means whereby the needle on its down stroke is assured against piercing and, therefore, breaking the thread.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings which form a part of this specification, and in which like characters of reference indicate the same or like parts:

Figure 1 is a plan view of the assembly of the apparatus embodying our invention;

Figure 2 is a view similar to Figure 1 but in side elevation;

Figure 3 is a side view of a portion of the apparatus, partly sectional, disclosing some of the features of our invention;

Figure 4 is a detail view of a clutching mechanism employed in our invention taken on line 4—4 of Figure 3;

Figure 5 is an enlarged view in section of one of the details of our apparatus;

Figure 6 is a view in section, taken substantially on the line 6—6 of Figure 5;

Figure 7 is a front view similar to Figure 3;

Figure 8 is a view in detail of a portion of the apparatus shown in Figure 7;

Figure 9 is a view in section, taken substantially on line 9—9 of Figure 7;

Figure 10 is an enlarged detail, in section, of a portion of our apparatus illustrating one of the mechanisms embodying our invention;

Figure 11 is an enlarged detail in section of a portion of our apparatus illustrating another of the mechanisms embodying our invention;

Figure 17 is a detail view in section, taken substantially on the line 17—17 of Figure 16; and

Figure 18 is a wiring diagram illustrating one feature of our invention.

Referring to the drawings, wherein we have disclosed the apparatus embodying our invention, and more particularly to Figure 3, we will first

describe the operation of the driving mechanism by means of which the needle is caused to be alternately grasped by the jaws of the upper and lower needle bars. There is provided suitable driving means such as a motor M, supported on a bracket 25. Mounted on motor shaft 26 is a gear 27 meshing with a gear 28 which is mounted on shaft 29, suitably supported, as shown, said shaft 29 having also mounted thereon a pulley

30. Pulley 30 may be made to drive pulley 32 by means of a belt 31. Pulley 32 is freely supported on a fixed, non-rotatable shaft 33 which is held in a support 34 fixed to the casing C. Positioned between pulley 32 and shaft 33 there is provided a collar 35 integral with and extending laterally

from pulley 32, said collar being adapted to rotate freely on shaft 33. Mounted on said collar 35 for rotation therewith is a gear 36, cam 37 and cam 38. By this construction it is seen that cams 37 and 38, and gear 36 are integrally connected to move as a unit when pulley 32 is driven by the belt 31. Said cams 37 and 38, as well as gear 36, are fixedly mounted on collar 35, which is designed to rotate freely about shaft 33. Cam 38 is provided with an annular groove in which rollers 39 are guided, said rollers being mounted on shafts 40 fixed to plates 41. It is seen from the above construction that plates 41 will be caused to oscillate with a predetermined regularity in accordance with the path of the annular groove in cam 38. This predetermined degree of oscillation of plates 41 may be made to be of the same amount as desired for the oscillation of upper needle bar 50 and lower needle bar 51 to alternately clutch the double pointed needle 52 after it has pierced the material to be stitched. The oscillatory motion of plates 41 may be transmitted therefrom to needle bars 50 and 51 by means such as rocker arms 53 and 54 pivoted to the casing at 55 and 56, respectively. Rocker arm 53 is connected to needle bar 50 by means of a link 57 and to plates 41 by means of a link 58, while rocker arm 54 may be connected to lower needle bar 51 by means of a link 59, and to plates 41 by means of a link 60.

During the operation of our apparatus, as fully described in our Patent No. 1,931,447, it was found that much time was lost by the operator in the threading of the needle and in securing one end of the thread in a fixed position until the stitching of the tie has been completed, at which time the thread had to be released by some means such as cutting with a knife or breaking.

We have, therefore, devised a novel mechanism by means of which the needle may be quickly threaded, after which one end of the thread is automatically grasped and held until the stitching of the tie has been completed, at which time the held thread is then automatically released. The mechanism by which we accomplish this may be described as follows:

A threader 65 (see Figure 3) having a threading hook 66 at one end and a handle 167 at the other end, is pivotally mounted on a shaft 168 in link 57 fixed to upper rocker arm 53. By this construction it is seen that hook 66, which is adapted to pierce the eye of the needle 52 to thread it, will always be in proper position to pierce the eye of the needle 52 when said needle is clutched by the upper needle bar 50. This is due to the fact that shaft 168, about which the hook 66 is pivoted, is caused to move with needle bar 50 to maintain a constant distance between shaft 168 and the eye of the needle.

In Figures 16 and 17 of the drawings we have shown the hook portion 66 of threader 65 after it has been swung around to pierce the eye of the needle 52. Thread T, which is shown looped over the hook, is ready to be threaded in the eye of the needle.

By referring to Figures 3 and 15, it will be noted that a pair of jaws 67 and 68 of a grasping device 70, supported on the machine casing, are shown held in effective or closed position by the action of a spring 71, whereas in Figure 16 it is seen that when the threader hook 66 has been inserted through the eye of the needle, the jaws 67 and 68 of the grasping device 70 have been forced open by means of a cam 69 rotatably

mounted on threader 65 and adapted to ride on lower jaw 68 to force said jaw 68 downwardly against the action of spring 71. As the threader 65 is pulled back to be withdrawn from the eye of the needle, hook 66 carries one end of the thread through the eye of the needle to thread the same and thence between the opened jaws 67 and 68. At the same time cam 69 allows lower jaw 68 to resume its normally closed position to grip the thread T between the teeth of the upper and lower jaws 67 and 68 to hold said thread in a fixed position. One end of thread T is thus held fixed for a predetermined time, such as when the tie has been completely stitched, when it is automatically released. Grasping device 70 is adjustably mounted on a plate 80 fixed by screws 81 to carriage 73, and held in any desired adjusted position by means of a bolt slideable in an elongated slot 82 in plate 80, and having its head 84 slideable in a complimentary slot 85 formed in carriage 73. The bolt may be secured in adjusted position by means of a nut 70a (Figures 14 to 16). We have provided the following means for automatically releasing the held thread at such predetermined time. A vertical plate 72 is mounted on the machine frame at one side of an intermittently traveling work carriage 73 (see Figure 14). The mechanism by which this work carriage is moved will become apparent as the description proceeds. Attached to plate 72 is a track 74 inclined with respect to the horizontal and suitably positioned and adapted to have a roller 75 ride thereon, said roller 75 being rotatably mounted on the extended end of lower jaw 68 (see Figure 16). Lower jaw 68 is made to pivot about an axis 76. When the work carriage 73 travels in the direction of the arrow (Figure 7) for a predetermined distance, roller 75 will ride on inclined track 74 to cause lower jaw 68 of the grasping device 70 to automatically release the thread T.

In stitching machines of the type described, wherein a looper is employed and where the loose end of the thread is pulled through the work after the completion of each stitch, it is particularly desirable to provide means to prevent the two strands of the thread cooperating with the needle and the work from becoming intertwined or entangled. Should the thread become entangled, the looper or the thread puller would tend to engage both strands of thread, and since one end of the thread is held fixed, it would be broken thus causing delay and inefficiency. To obviate this disadvantage we have devised novel thread holding mechanisms designed to constantly maintain the thread in position to prevent tangling. We will first describe the operation of our thread holding mechanism as applied to the needle, when said needle is connected to the upper needle bar 50. Then the operation of the mechanism which we employ to hold the thread when the needle is connected to the lower needle bar 51 will be described.

In Figures 7 and 8 of the drawings there is disclosed upper needle bar 50 slidably operating in the frame C, said frame having attached thereto a bracket 80a. An arm 81a is pivoted at one end to bracket 80a at a point 82a. Arm 81a may be held pressed into engagement with needle 52 by suitable means such as an adjustable spring 83. A stop 84a, fastened to the frame of the machine, is provided to limit the pressure of arm 81a against the needle 52 to prevent breaking of the needle. On the opposite side of the needle 52 from that of arm 81a we provide another arm 86.

pivotedly mounted on the machine casing at 87 and held in engagement with needle 52 by suitable means such as a spring 88. Arm 81a is provided with a cam portion 85a adapted to cooperate with a projecting lug 89 fixed to needle bar 50.

When the needle bar 50 is in raised position, as shown in Figure 7, arms 81a and 86 serve to maintain the strands of the thread in proper alignment to prevent entanglement. When needle bar 50 moves downwardly a wedge-shaped needle chuck 90, fixed to the lower end of needle bar 50, acts so as to move arm 86 away from needle 52 against the action of spring 88, while at the same time lug 89 contacts the cam portion 85a to move arm 81 away from the needle against the action of spring 83. Thus it is seen that arms 81a and 86 are caused to be spread apart to free the thread for effective use to permit the thread to be acted upon by a specially designed looper which will be described in detail as the description proceeds. When needle bar 50 returns upwardly, arms 81a and 86 re-engage the needle 52 to hold the strands of the thread.

Another thread holding mechanism is also provided to hold the strands of the thread when the needle is connected to the lower needle bar 51. Referring to Figure 3, there is disclosed a cam member 91 fixed to rocker arm 54. Cam member 91 is provided with a slotted portion 92. A link 93 is pivotally connected to the machine casing at a point 94, said link 93 having fixed thereto a pin 95 adapted to engage the slot 92 to cause link 91 to travel in an oscillatory path about pivot 94 whenever rocker arm 54 is moved. A forked member 96 is pivotally attached to link 93 at 97 at one end, and to a lever 98 at a point 99. Lever 98 is pivoted to the machine casting at 100, as shown in detail in Figure 10. Forked member 96 has extension arm members which are adapted to straddle and press against the needle 52 at opposite side thereof to maintain the thread in proper alignment to prevent entanglement. Cam member 91 is so designed as to maintain the lower thread holding mechanism, as just described, in effective position until such time as the thread is acted upon by a specially designed thread puller, similar to that shown and described in our Patent No. 1,931,447, and which will be discussed more fully as the description proceeds.

To further increase the efficiency of operation of our stitching machine, we have devised a novel mechanism which we call a looper, the operation of which will now be explained. Referring first to Figure 7 of the drawings, there is disclosed a looper 105, one end of which is pivotally mounted on the machine casing at a point such as 106. Journalized in said machine casing is a shaft 107 (see also Figure 1) having mounted thereon at one end a lever 108. Said lever 108 is connected to looper 105 by means of a link 109, one end of which is pivotally fastened to looper 105 at a point such as 110, the other end being pivotally connected to lever 108 at 111. Thus it can be seen that when shaft 107 is rotated, looper 105 will be caused to oscillate about pivot 106. The degree and regularity of this oscillation may be governed by means of a lever 115 mounted on shaft 107 and provided with a cam follower, such as a roller 112 fixed to shaft 114, adapted to ride on a cam 37.

The contour of cam 37 may be such as to cause looper 105, through the linkage system just described, to oscillate about its pivot 106 at predetermined intervals from an inoperative position

A, shown in dotted lines in Figure 7, to advanced operative position such as shown in full lines in Figures 11 and 13, and engage the thread after it has been moved slightly away from the needle 52 upon the downward travel of the upper needle bar. Looper 105, which may use any suitable hook means for engaging the thread, such as a spool-like projection 116 mounted on a pin 105a carried in arm 105, travels to the left from its inoperative position (as viewed in Figure 7). Spool-like projection 116 (see Figure 3) has associated therewith a roller 116a rotatably mounted on pin 105a carried by the looper arm. In this way the looper engages the thread, forms a loop (as shown in Figures 11 and 13), and exerts sufficient pulling force on the loose end of the thread to pull a small portion thereof back through the work and thereby provide slack therein. When looper 105 occupies the position shown in Figures 11 and 13, and thread puller 120 engages the thread beneath the work and adjacent the lower needle bar, roller 116a acts as a guide for the loose end of the thread as it is pulled through the work by the thread puller 120 and deposited about drum 121. From the above description of the operation of the looper, it is apparent that the loose end of the thread T is prevented from becoming entangled and broken when the needle 52 is shifted from the upper needle bar, as in Figure 7, to be clutched by the lower needle bar as shown in Figure 10. Furthermore, the thread will be properly guided by roller 116a with a substantial elimination of friction on the thread as it is pulled by the puller 120. Also, due to the provision of slack, each stitch formed will be properly tensioned in the material being sewed. This last feature is also enhanced by the fact that cam 37 is so designed that a slight rearward or return movement is imparted to looper 105 as the needle moves through the work on its downward movement. The mechanism for operating the looper 105, just described, is designed to act in cooperative relation with the thread holding means hereinabove described in connection with the upper needle bar 50.

The mechanism which we employ in our improved apparatus to engage the loops as they are formed from the thread in stitching and to draw or pull out the free end portion of the thread after each stitch may be similar to that shown and described in our Patent No. 1,931,447, hereinbefore mentioned. The operation of the above described mechanism will be clearly understood from a study of Figures 3 and 7 of the drawings in which it is seen that gear 36 is mounted for rotation with pulley 32, and that when said gear 36 is rotated it causes a thread puller 120 to be carried in a circular path around the periphery of a stationary grooved drum 121, by means of a chain of gears 122 (Figure 3), 122', 123 and 124.

The following mechanism may be employed to cause thread puller 120 to travel in its circular path:

Gear 124 is so mounted that it is in eccentric relation to the axis of the grooved drum 121. Fixed to gear 124 for rotation therewith is an annular plate 124'. The thread puller 120 is fixed to the outer end of a carrier arm 125, said carrier arm being pivoted at its inner end to the drum 121 at a point 126 coincident with the center of said drum 121. Carrier arm 125 is provided with a longitudinal slot 127 into which a block 128, fixed to the outer edge of annular disc 124', is adapted to slide. Thus it is seen that when gear 124 is rotated, the thread puller 120 is caused to travel

around drum 121. The mechanism for operating the thread puller, as just described, is designed to act in cooperative relation with the thread holding means hereinbefore described in connection with the lower needle bar 51.

The function of the stationary circular grooved drum 121 is similar to that shown and described in our Patent No. 1,931,447. Briefly stated, it is to support the loose portion of the thread on the periphery of said drum 121 after the said thread has been pulled out from the fabric by the thread puller 120. Figures 11 and 13 clearly illustrate two steps in this action. Drum 121 may be provided with grooves 129 as shown in Figure 12, to prevent entanglement of adjacent strands of the thread while they rest on said drum 121. To further safeguard against the possible entanglement of the loose portion of the thread while it is being guided onto drum 121 and into grooves 129, we have devised a novel thread holding means which may comprise a plurality of brushes 130 held in engagement with grooves 129 of the drum 121 by means of adjustable springs 131 (see Figure 9). Brushes 130 are pivotally fastened to the machine casing at suitable positioned points, such as at 132. These brushes 130 serve to hold the thread in its own groove on the drum 121 to prevent sagging and resulting entanglement. The thread puller 120 is adapted to readily pass through the brushes 130 as it travels in a circumferential path around said drum.

We have also devised a simplified and more efficient mechanism than heretofore employed for intermittently advancing the platform carrying the fabric to be stitched.

By referring to the drawings, the operation of the above mentioned mechanism will be clearly understood. In Figure 7, we have disclosed a portion of the work carriage or the traveling platform 73 adapted to travel along any suitable guide means or tracks, such as shown and described in our Patent No. 1,931,447. On the underside of said platform 73 there is provided a toothed rack 135. On a shaft 137 fixed to the machine casing C we mount a gear 136 designed to mesh with said rack 135. The means by which gear 136 may be intermittently rotated to intermittently advance the platform 73 may be described as follows:

On the shaft 137 we also mount a notched wheel 138 having a series of spaced notches 140 arranged circumferentially of said wheel 138. Mounted for rotation with gear 122' is a cam member 141 having an extended portion 142 adapted to cooperate with slots 140. Cam member 141 is so designed that with each revolution thereof the extended portion 142 will successively engage a slot 140 to rotate wheel 138 a predetermined amount. Wheel 138 will then rotate shaft 137 and gear 136 mounted thereon to advance platform 73 a predetermined distance in the direction shown by the arrow. Gear 122' is mounted on the same shaft as gear 122 and rotates therewith. Gear 122 is driven by gear 36 which in turn is fixed to the pulley 32 for rotation therewith. The mechanism just described is so designed as to cause platform 73 to travel a predetermined amount after each stitch.

It is well known by those familiar with the art that the needle employed in machines of the type described must be occasionally changed for various reasons. It is desirable, therefore, that this be done as quickly as possible. To facilitate the quick removal and replacement of the needle, we have devised a mechanism which will now be de-

scribed. Referring first to Figure 5, we have shown an enlarged view in section of the mechanism of the upper needle bar 50 to which is screwed at its lower end a tapered chuck 90.

5 Within the hollowed interior of chuck 90 we provide three balls B (see Figure 6) arranged so as to permit needle 52 to be inserted between them and held thereby. When the balls B are pressed downwardly, the tapered portion of chuck 90 forces them together to grip the needle 52. This downward pressure is applied by means of a spring 150 pressing against a shank 151 which in turn presses on the balls B. The upper end of said spring 150 abuts against a member 152 screwed into the top portion of needle bar 50. The upper end of shank 151 extends through member 152 and is fixed to a stop 153, the lower end of which is provided with a hollow portion adapted to allow needle bar 50 to slide therein. 10 Thus it can be seen from the above description that when the stop 153 is raised in the direction of the arrow while needle bar 50 is held stationary, it will carry with it shank 151. This will act so as to release the pressure on balls B to allow the needle 52 to be easily removed and replaced. Any suitable means for raising the stop 153 may be employed, such as a forked handle 155 (Figures 7 and 8) pivotally mounted in a frame 156 fixed to the machine casing C. When handle 155 is pressed downwardly, the lower forked end of said handle will engage the underside of stop 153 to raise the same and thereby release needle 52 in the manner just described.

It has been found in the course of the operation 35 of stitching machines of the character described, where the upper and lower needle bars are in alignment, that occasionally the thread would be found to overlie the hole of the lower chuck so that when the needle travels downwardly to be grasped by the lower chuck it is apt to pierce the thread which interrupts its path, to break said thread. This obviously causes a delay inasmuch as it then becomes necessary for the operator to stop the machine and rethread the needle and start all over again. We have devised a novel 40 means for overcoming this disadvantage which consists in positioning the needle hole in the lower needle chuck 90' to one side of the pointed portion thereof. By this construction it is seen that the thread T is not able to rest over the needle hole in lower chuck 90', but will tend to slide down to either side due to the pointed construction as well as the positioning of the needle hole.

When operating machines of the character described by power means, such as a motor, it has been found desirable at times for certain reasons, such as making trial stitches, to operate the machine by hand. The means by which we accomplish this in connection with our apparatus may be described as follows:

Positioned within the central portion of pulley 32 is a clutch mechanism 160 shown in detail in Figure 4. This mechanism operates on a principle similar to that used in free wheeling devices. A disc member 163, of the clutch 160, is rigidly attached to a collar 161 which idles on shaft 33. A plurality of spaced notched portions 162 are cut out of the circumference of disc 163. Into these notches are fitted rollers 164. It will be noted 55 that disc 163 is of lesser diameter than the interior opening in pulley 32, thus permitting said disc 163 to rotate freely within the pulley 32. Fastened to the disc portion 163 of the clutch 160 at one end is a hand wheel 39, as shown in Figure 3, adapted to rotate with said disc 163.

It will be seen from the above described construction, that whenever the hand wheel 39' is rotated in a clockwise direction, as indicated by the arrows in Figures 3 and 4, the rollers 164 will be held in notched portions 162 and disc 163 will be permitted to rotate freely without effecting the rotation of pulley 32. However, when the hand wheel 39' is rotated in a counterclockwise direction, opposite to that shown by the arrows in Figures 3 and 4, rollers 164 will then be freed from the notched portions 162 to engage the inner surface of pulley 32 to lock disc 163 to said pulley for rotation therewith. Thus it is seen that whenever it is desired to operate the stitching machine by hand, it is merely necessary to turn the hand wheel in a direction opposite to that shown by the arrows in Figures 3 and 4 and in so doing, the machine will operate similarly to that of the operation when power means is used.

Should it be desired to operate our apparatus automatically, we have provided an automatic switching mechanism adapted to close a circuit to start the motor when a lever mechanism is tripped and to cause said circuit to be broken to stop the apparatus when the work platform has traveled a predetermined distance.

In Figure 18 we have shown a wiring diagram illustrating one means for accomplishing this result. When lever 170 is turned in the direction of the arrow B, a catch mechanism 171 is tripped to close the contacts 172 of the switch S by means of a spring R in order to complete a circuit from a source of current supply through the motor M which is energized to cause platform 73 to travel in the direction of arrow A. Fastened to platform 73 and traveling therewith is a projecting lug 173 adapted to strike against a projecting portion S' of switch S. Lug 173 may be positioned at a predetermined distance from the projecting portion of switch S', such for example as is necessary for the complete stitching of a tie. When lug 173 strikes projecting portion of switch S', contacts 172 are opened against the action of the spring R to break the circuit and stop motor M. The lever 170 may then be made to re-engage catch 171 to hold contacts 172 open until it is desired to operate the machine to stitch another tie.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth, or shown in the accompanying drawings, is to be interpreted as illustrative and not in a limiting sense.

What is claimed is:

1. In a sewing machine, the combination of a needle having a thread associated therewith, a needle bar cooperating with said needle, a stationary support for said needle bar adapted to permit vertical movement of said needle bar, means cooperating with opposite sides of said needle for maintaining said thread in proper relationship with said needle to prevent entanglement of said thread, said last named means comprising a pair of members normally in contact with opposite sides of said needle, means supporting each of said members for independent movement to and from each other, and means for moving said members in opposite directions away from said needle.

2. In a sewing machine, the combination of a

needle, having a thread associated therewith, a needle bar cooperating with said needle, a stationary support for said needle bar adapted to permit vertical movement of said needle bar, a looper member for forming said thread into a loop, means for maintaining said thread in proper relationship with said needle to prevent entanglement of said thread, said last named means comprising members pivotally mounted on said stationary support, and normally engaging opposite sides of said needle, and means carried by said bar for moving said members away from said needle.

3. In a sewing machine, the combination of a needle having a thread associated therewith, a needle bar cooperating with said needle, a stationary support for said needle bar adapted to permit vertical movement of said needle bar, means for maintaining said thread in proper relationship with said needle to prevent entanglement of said thread, said last named means comprising opposed members mounted on said stationary support, means for moving said members towards each other to engage opposite sides of said needle, and means coacting with said members for moving said members out of engagement with the opposite sides of said needle at predetermined intervals to free said thread for effective use.

4. In a sewing machine, the combination of alternately operating needle bars, a needle having a thread associated therewith, means to alternately connect the needle with each needle bar, stationary supports for said needle bars adapted to permit vertical movement of said needle bars, means associated with each of said needle bars for maintaining said thread in proper alignment with said needle to prevent entanglement of said thread, said last named means being mounted on said stationary supports and adapted to engage opposite sides of said needle, and means whereby said thread maintaining means is caused to disengage the opposite sides of said needle at predetermined intervals to free said thread for effective use.

5. In a sewing machine, the combination of a needle having a thread associated therewith, a needle bar cooperating with said needle, a stationary support for said needle bar adapted to permit vertical movement of said needle bar, and means cooperating with opposite sides of said needle for maintaining said thread in proper relationship with said needle to prevent entanglement of said thread, said last named means comprising a pair of opposed members pivotally mounted on said stationary support and movable in opposite directions to and from each other into and out of engagement with said needle.

6. In a sewing machine, the combination of a needle adapted to receive a thread, a needle bar cooperating with said needle, a stationary support for said needle bar adapted to permit vertical movement of said needle bar, means for maintaining said thread in proper relationship with said needle to prevent entanglement of said thread, said last named means comprising opposed members movably mounted on said stationary support, means for moving said members towards each other to engage opposite sides of said needle, and means whereby said members are caused to disengage the opposite sides of said needle at predetermined intervals to free said thread for effective use.

7. In a sewing machine, the combination with a

needle bar and a needle having a thread asso-

ciated therewith, a work table, a support mounting said needle for movement to and from said table, mechanism including oppositely movable fingers located above said table coacting with opposite sides of said needle for maintaining said thread in proper alignment relative to said needle to prevent entanglement of said thread, and means operative in timed relation to the movement of said bar for effecting the movement of said mechanism into and out of engagement with said needle above said table.

8. In a sewing machine having a work supporting table, mechanism for projecting a needle and a thread having a loose and a fixed end back and forth through work to be sewed and forming loops in said thread alternately above and below said table, a looper located above said table, mechanism for moving said looper into engagement with a loop of thread above said table to pull thread through said work, said mechanism including means for interrupting the travel of said looper while holding said thread engaged thereby away from said work and said needle, a thread puller mounted beneath said table, and mechanism operative after said looper has engaged a loop of thread above said table for moving said puller into engagement with a loop of thread formed beneath said table to pull the entire loose end of said looper supported thread over said looper and through said work.

9. In a sewing machine, the combination with a needle and an upper and a lower needle bar for projecting a needle with a thread having a loose and a fixed end back and forth through material to be sewed, and means for moving said upper bar towards said material to form a loop in said thread and for moving said lower bar upwardly towards said material to form a loop in said thread below said table on alternate movements of said bars, of a looper device mounted above said table, mechanism for moving said device from an inoperative position into engagement with said loop of thread formed above said table to pull a portion of said thread through said work and support it thereabove, said mechanism including means for interrupting the travel of said looper while holding said thread, a thread puller mounted below said support, means operative after the engagement of said first-named loop of thread by said looper device and while said thread is supported thereby for moving said thread puller to engage said second loop of thread beneath said support to pull said loose end of said thread over said looper device and through said work.

10. In a sewing machine having a needle and means for projecting said needle and a thread with a loose and a fixed end back and forth through work to be sewed, a material support, a revolving thread puller located beneath said support, a looper located above said support and arranged to pull a portion of said thread through said work, mechanism for moving said looper to engage and support a portion of said thread away from said needle, including means for interrupting the travel of said looper while said thread is supported thereby, and separate means operative independently of said looper operating mechanism for moving said puller to pull said loose end of said thread from said looper and through said work.

11. In a sewing machine, the combination with a pair of needle bars and means for moving said bars, and projecting a needle with a thread hav-

ing a fixed and a loose end back and forth through material to be sewed and form loops alternately adjacent said bars, of a thread puller located adjacent one of said bars, a slack forming and thread supporting member positioned adjacent the other of said bars, mechanism for moving said member to engage alternate loops formed in said thread adjacent said last-named bar, said mechanism including means for interrupting the travel of said member while holding said thread away from said work, and means for moving said puller into engagement with each alternate loop formed adjacent said first-named bar to pull said loose end of said thread through said work while said thread is held by said member.

12. In a sewing machine, the combination with a needle and alternately operating upper and lower needle bars, of a support for said needle bars, means to alternately connect said needle to each needle bar for projecting a thread having a fixed and a loose end back and forth through work to be sewed, means timed with said alternately operating needle connecting means and cooperating with said upper needle bar for forming said thread into a loop, said last-named means comprising a looper device, mechanism for moving said device past said upper bar from an inoperative position at one side of said upper bar into engagement with said looped thread to pull a portion only through said work and displace said thread relative to said needle, said mechanism including means for supporting said thread away from said work, and a thread puller cooperating with said device, driving means for operating said puller for pulling the loose end of said thread through said work while said thread is supported by said device, and means forming a part of said mechanism operative at the conclusion of the operation of said puller driving means for returning said device in a different direction past said upper bar to said inoperative position after the operation of said puller.

13. In a sewing machine, the combination with a needle, of a needle bar cooperating with said needle, a support for said bar constructed and arranged to move said needle and a thread having a fixed and a loose end back and forth through material to be sewed, a material supporting surface, means for moving said bar relative to said surface to form loops in said thread, a looper device mounted for movement to and from said bar, and mechanism for moving said device from an inactive position adjacent one side of said bar into engagement with each loop as formed to pull a portion only of said thread back through said work and displace said thread away from the path of travel of said needle, said mechanism including means for interrupting the movement of said device at the other side of said bar for supporting said thread away from said work during stitch formation, and means for returning said device to said inactive position for the formation of the next stitch.

14. In a sewing machine, the combination with a needle and an upper and a lower needle bar for projecting the needle and a thread having a fixed and a loose end back and forth through work to be sewed, means for moving said upper bar and needle downward to form loops in a thread carried by said needle alternately on opposite sides of said work, a looper device located adjacent said upper needle bar, mechanism for moving said device into engagement with each loop formed ad-

jacent said upper bar to displace thread away from said needle and support the same away from said work, said mechanism including means for interrupting the movement of said device while said thread is supported away from said work, a thread puller positioned adjacent said lower bar, and means operative while said device is supporting said thread for moving said puller to pull said loose end of said thread from said looper and through said work.

15. In a sewing machine, the combination with a needle and a pair of opposed needle bars arranged in opposition one to the other for projecting said needle and a thread back and forth through material to be sewed, of means for moving one of said bars downward to form a loop in said thread proximate said material, opposed, separately movable means mounted adjacent opposite sides of said bar and cooperating with said needle to prevent said thread from crossing its path, a looper member, means mounting said member for movement back and forth along the same path past said bar, means for operating said member in conjunction with said opposed separately movable means, mechanism for moving said member from an inoperative position to engage a part of said loop away from said needle to provide slack in said thread and support the same in forming each stitch, said mechanism including means for interrupting the movement of said member for a part of each cycle, and means for returning said member to said inoperative position.

16. In a sewing machine, the combination with a needle and a pair of opposed needle bars arranged in opposition one to the other for projecting said needle and a thread having a fixed and a loose end back and forth through material to be sewed, of means for moving one of said bars downward to form a loop in said thread proximate said material, means cooperating with said

- needle and coacting with said bar to prevent said thread from crossing its path, a looper member, means mounting said member adjacent said bar, mechanism operating in conjunction with said last-named means for moving said member into engagement with a part of said loop to displace a portion of said thread away from said needle to provide slack in said thread, said mechanism including means for interrupting the movement of 5 said member to support said thread away from said work during each complete movement of said member, and means operating in timed relation to the movement of said bars for pulling said loose end of said thread through the work and over said member while the movement of said member is interrupted.
17. In a sewing machine, the combination with a needle, and an upper and a lower needle bar coacting with said needle, of supports for said bars constructed and arranged to move said needle and a thread having a fixed and a loose end back and forth through material to be sewed, means for moving said upper bar downward with said needle to form a loop in said thread adjacent said 20 material, a single looper member, mechanism for moving said looper member back and forth relative to said upper bar along an arcuate path less than 180° to engage and pull a portion only of said looped thread and provide slack therein, said 25 mechanism including means for interrupting the movement of said member during a portion of its travel, and a thread puller positioned for coaction with said lower bar while the movement of said member is interrupted to pull the loose end of 30 said thread over said member and through said material.
